CLAIM

We claim the ornamental design for hoop portions of a sports racquet, as shown and described.

DESCRIPTION

FIG. 1 is a front perspective view of the hoop portions of a sports racquet;

FIG. 2 is a front view of the hoop portions of a sports racquet of FIG. 1;

FIG. 3 is a first side view of the hoop portions of a sports racquet of FIG. 1;

FIG. 4 is a second side view of the hoop portions of a sports racquet of FIG. 1 opposite the first side view;

FIG. 5 is a top view of the hoop portions of a sports racquet of FIG. 1; and,

FIG. 6 is a bottom view of the hoop portions of a sports racquet of FIG. 1.

The ornamental design that is claimed is shown in solid lines in the drawings. The broken (dashed) lines shown in FIGS. 1 through 6 are included for the purpose of illustrating environmental elements only and form no part of the claimed design.
